UNITED STATES PATENT OFFICE.

CHARLES F. LORENZ, OF CLEVELAND, OHIO, ASSIGNOR TO GENERAL ELECTRIC COMPANY, A CORPORATION OF NEW YORK.

ELECTRICAL CONTROLLING DEVICE.

1,297,879.

Specification of Letters Patent.

Patented Mar. 18, 1919.

Application filed April 12, 1917. Serial No. 161,431.

To all whom it may concern:

Be it known that I, CHARLES F. LORENZ, a citizen of the United States, residing at Cleveland, county of Cuyahoga, State of 5 Ohio, have invented new and useful Improvements in Electrical Controlling Devices, of which the following is a specification.

My invention relates to the control of 10 electrical devices of various types but is particularly adapted to the control of electric illuminating and heating devices.

My invention is especially adapted to the control of electrical devices embodying conductors of high temperature coefficients, as for instance, metallic filament lamps, and in the present application is applied to the control of tungsten filament lamps which, as known, have a large positive temperature 15 coefficient. The object of my invention is a simple arrangement whereby the illumination intensity of a metallic filament may be simply and easily controlled either at the lamp socket or at a point remote therefrom, 20 without the necessity of the usual additional circuits and switches accompanying prior systems of regulation. In accordance with my invention I take advantage of the high positive temperature coefficient of the filament to either run the lamp at a high or at a low intensity and in carrying out my invention I insert in series with the filament a 25 miniature electromagnet which is designed with sufficient power to operate its armature when the filament is cold, but when the filament is heated up, as by momentarily passing a current therethrough, the current flowing under these conditions is insufficient to operate the armature and the armature 30 remains in the open position during the continuance of the flowing of the current in the circuit. The armature of the electromagnet is adapted to short circuit a resistor in series with the filament and this resistor 35 may be an auxiliary filament in the incandescent lamp bulb which is designed to glow dimly when the armature is in the open position. In accordance with this modification the electromagnet is inclosed in the base

of the lamp but in another modification the 50 magnet and resistor are inclosed in a connector or adapter which is adapted to be inserted in the circuit either at the lamp socket or at any point between the lamp socket and controlling switch. The operation in either case is the same and the control is effected by simply turning on and off the current. For instance, the high intensity is obtained by simply closing the switch once, the first rush of current due to 55 the low cold resistance of the filament being sufficient to operate the armature and short circuit the resistor. To operate "dim" or at low intensity the switch is closed momentarily, then off, and then on again, these 60 three operations rapidly following each other. In the latter case the first rush of current heats the lamp filament and causes a substantial rise in its resistance and when the circuit is momentarily opened 65 again the armature of the magnet which has closed during the first rush of current falls away and when the circuit is closed the second time the current under the high 70 temperature conditions of the filament is insufficient to operate the magnet and the resistor remains in circuit and causes the lamp to operate "dim." This arrangement has a 75 number of advantages, among which may be mentioned the simplicity of the control 80 whereby no additional wiring is necessary and the usual wall switch may be used to control the lamp. In fact any switch anywhere in the circuit may be used with equal 85 facility for controlling the lamp.

For other advantages of my invention and for a better understanding thereof, reference may be had to the drawings accompanying this specification, Figure 1 of which is a side view of an incandescent lamp embodying my invention, Fig. 2 is a sectional view thereof, Fig. 3 is a modification of my invention.

Referring to the drawings, an incandescent lamp 1 is provided with a base 2 and 90 in this base is inclosed a small electromagnet 3, whose armature 4 normally rests in the open position as shown against an ad-

justable stop 5, this armature 4 being adapted to be pulled over against the core of the magnet against the tension of the leaf spring support of the armature. This controlling 5 electromagnet rests on an insulating partition 6 and the whole compartment may be sealed as shown and filled with some insulation liquid, as a suitable oil, the oil in addition to its insulating qualities serving to 10 damp out vibrations of the armature 4 when the lamp is energized by alternating currents. A conventional switch 7 is illustrated which may be either the switch in the lamp socket or may be a remote switch located on the wall or at some other convenient 15 point of control. In Figs. 1 and 2 a resistor 8 is connected in the circuit and consists of an auxiliary filament and is adapted to operate "dim" when the main filament 9 20 is not illuminated. The magnet coil 3 is at all times, as illustrated, connected in circuit while the resistor 8 is adapted to be short-circuited by the engagement of the armature 4 with the core of the electromagnet. 25

The operation is as follows: When the switch 7 is closed the current from the positive side of the line throws through the lamp base shell to the leading in wire 10, from the 30 leading in wire 10 to and through the main filament 9 to leading in wire 11. From leading in wire 11 the current passes down again into the auxiliary filament 8 through one of its leading in wires and back again 35 through the other leading in wire through conductor 12 to the core of the electromagnet and from this core the circuit continues through the coil 3 to the negative side of the line. The filament 9 being cold and, therefore, 40 at a low resistance, a rush of current occurs which is sufficient to operate the armature 4 of the magnet and the closing of this armature short circuits the auxiliary filament 8 and the lamp continues to operate 45 bright until the switch 7 is opened. It is understood that once the armature 4 is closed the current flowing through the electromagnet is sufficient to retain the same in the closed position, even under the low current 50 conditions. To operate the lamp "dim" the switch 7 has only to be opened momentarily and long enough for the armature 4 to be withdrawn from engagement with the core, then quickly closed again before the filament 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900

cuit to the lamp at any convenient point. In the particular arrangement shown the connector embodies a combined screw base and shell socket which may be inserted in the usual fixtures and receive a lamp of standard construction therein. This embodies an electromagnet coil 3' and its armature 4' and the resistor 8'. This resistor 8' is conventionally illustrated and may assume any suitable form for inclosure in the adapter 70 and itself may be of a positive temperature coefficient like the filament with which it is inserted in series. The operation of this modification is similar to the operation of the modification illustrated in Figs. 1 and 2, 80 except that in this case the resistor 8' is not adapted to furnish any of the illumination and the main filament of the lamp operates both bright and low dependent upon whether the resistor is in circuit or short circuited by 85 the electromagnet.

What I claim as new and desire to secure by Letters Patent of the United States, is,—

1. In a control system, an electrical device to be controlled embodying a conductor of 90 a high positive temperature coefficient, a resistor in series with the conductor and an electromagnet adapted to short circuit said resistor when the circuit is first closed and to retain the short circuit during the continued operation of the device, the power of 95 said electromagnet being insufficient to short circuit the resistor when the temperature of the conductor is high.

2. In a control system an electrical device 100 to be controlled embodying a conductor of a high temperature coefficient, a resistor in series with the conductor, and an electromagnet in series therewith which has sufficient power to short circuit said resistor under the cold conditions of the device, the power being insufficient to short circuit the 105 resistor under higher temperature conditions.

3. In a control system a metallic filament 110 incandescent lamp, a resistor in series with the filament and an electromagnet adapted to short circuit said resistor when the circuit is first closed and retain the short circuit during the continued burning of the lamp, 115 the power of said magnet being insufficient to short circuit the resistor under the influence of the low current under the high temperature condition of the filament.

4. In a control system a tungsten filament 120 incandescent lamp, a resistor in series with the lamp, and an electromagnet in series therewith adapted to short circuit the resistor when the circuit is first closed, the power of said electromagnet being sufficient 125 to retain the short circuit during the continued burning of the lamp, but insufficient to operate the short circuit under the low current and high temperature conditions of the filament.

5. An adapter for insertion in the circuit of a metallic filament lamp embodying a resistor and an electromagnet adapted to short circuit said resistor when the circuit is first closed and retain the short circuit during the continued closure of the circuit, the power of said magnet being insufficient to short circuit the resistor under the low current and high temperature conditions of the filament.
- 10
- In witness whereof, I have hereunto set my hand this 10th day of April, 1917.

CHARLES F. LORENZ.
